2 Claims. (Cl. 103—129)

ABSTRACT OF THE DISCLOSURE

A device for locking a piston against rotation in one direction relative to the circular chamber wall of a rotary engine. The device includes a groove in the piston opening towards the circular wall, and a movable member in the groove suitably dimensioned to wedge itself between the groove bottom and the circular wall when the piston exhibits a tendency to rotate in the said one direction.

The present invention, which is a continuation-in-part of my copending application Serial No. 387,977, filed August 6, 1964, and now issued as U.S. Patent No. 3,282,258, relates generally to rotary engines and more particularly to an improved means for controlling the direction of piston rotation.

Engines of the above-mentioned type usually include a plurality of pistons mounted within a generally circular housing for rotation about a common axis. Power for the engine is derived from the expansion of gases in the chambers formed between the pistons. Means must therefore be provided for locking each piston against rotation in one direction while at the same time allowing for rotation of the next adjacent piston in the opposite or "drive" direction. It is to this end that the present invention is directed.

A primary object of the present invention is the provision of a clutching device on each piston, which device cooperates with an adjacent wall of the engine housing to lock the piston against rotation in one direction regardless of the position of the piston within the housing.

Another object of the present invention is to provide a clutching device of the aforementioned type, the operation of which is controlled solely by the relative movement of the piston on which it is carried.

These and other objects and advantages of the present invention will become more apparent as the description proceeds with the aid of the accompanying drawings in which:

FIG. 1 is a partial vertical sectional view of a rotary engine embodying the concepts of the present invention;

FIG. 2 is a sectional view taken along line 2—2 of FIG. 1;

FIG. 3 is a sectional view depicting an alternate embodiment of the invention; and,

FIG. 4 is a sectional view showing still another embodiment of the invention.

Referring initially to FIGS. 1 and 2 wherein are best shown general features of the present invention, a rotary engine of the type described in my copending U.S. application Serial No. 387,977 (now issued as Patent No. 3,282,258) is shown at 10, the housing of which is comprised in part of an outer circular wall 12 and end plates 14 and 16. A plurality of pistons, two of which are indicated in FIG. 1 by the reference numerals 18 and 20 are mounted for rotation within the housing about a central shaft 22. The pistons are each provided with locking or clutching devices 23a and 23b, a more complete description of which will hereinafter be provided. The clutching devices prevent rotation of the pistons in the counterclockwise direction while at the same time allowing for piston rotation in the opposite or "drive" direction.

The pistons 18 and 20 together with circular housing

2

wall 12 and end plates 14 and 16 cooperate to define a chamber 24, the volume of which will vary during operation of the engine to thus provide a variable compression feature. A conventional spark plug 26 (one of several positioned at selected spaced points around the housing wall 12) is threaded into a passageway 28, the latter extending radially through wall 12 into communication with chamber 24. Means (not shown) are provided for delivering a charge of fuel such as atomized gasoline to the chamber 24. The fuel is then compressed between pistons 18 and 20 and ignited by spark plug 26. The expanding gases resulting from combustion exert forces on both pistons, which forces are indicated schematically in FIG. 1 by the arrows 30. These forces push piston 20 in a clockwise or "drive" direction while piston 18 is held stationary by the locking action of clutching device 23a.

The means for providing a drive connection between the pistons and shaft 22 as well as the fuel injection and exhaust means are described in my copending application referred to above and since these components do not form a part of the present invention, they will not be dealt with further here. The present invention, which relates solely to the clutching devices employed to control the direction of piston rotation, will now be described in greater detail.

The embodiment of the invention illustrated in FIGS. 1 and 2 is comprised in part of a groove 30 machined into the end face or surface 32 of each piston. The grooves 30, which open towards the circular wall 12 of the engine housing, are each provided with bottom surfaces 34 which slope downwardly in a direction opposite to the clockwise or drive direction from a shallow end at 36 to an opposite end of increased depth at 38. The grooves 30 cooperate with circular wall 12 to define elongated chambers which in the embodiment herein disclosed, extend across the width of each piston in a direction parallel to the rotational axis of shaft 22 (see FIG. 2).

Locking means, illustrated in FIGS. 1 and 2 in the form of cylindrical rollers 40a and 40b are movably contained in the grooves 30. Each roller is provided with a diameter which is at least equal to and preferably slightly greater than the minimum radial distance between the bottom 34 of groove 30 and circular wall 12. It is to be understood, however, that the maximum diameter of rollers 40a and 40b must be less than the maximum distance between the bottom of groove 30 and wall 12. By keeping the roller diameters within these dimensional ranges, lateral movement of the rollers within the grooves 30 will be possible, the said movement in turn being controlled by the direction of rotation of the pistons. More particularly, any tendency of a piston to rotate in a counterclockwise direction will cause the roller carried thereon to move into the shallow portion of groove 30 where it will become tightly wedged between the groove bottom 34 and circular wall 12. This wedging action will effectively prevent counterclockwise rotation of the piston while at the same time providing an effective seal between the piston and the circular housing wall 12. The clutching device 23a in FIG. 1 is shown in this condition with the roller 40a tightly wedged between the bottom 34 of groove 30 and the circular wall 12.

Any tendency of a piston to rotate in a clockwise direction will automatically result in the clutching device carried thereon being disengaged. In FIG. 1, clutching device 23b is in this condition due to the movement of piston 20 in a clockwise direction. More particularly, the clockwise movement of the piston has caused roller 40b to be displaced towards the deeper end 38 of groove 30, thus moving it out of wedged engagement between groove bottom 34 and wall 12.

An alternate embodiment of the invention is illustrated in FIG. 3 wherein the groove 42 has been slightly modified

by providing a bottom 44 which slopes gradually from the end face 46 of piston 47 towards a deep end 48. In this embodiment, the locking means is comprised of a generally wedge-shaped block 50 having a maximum dimension measured radially from the rotational axis of shaft 22 which is greater than the minimum radial distance between the bottom 44 of groove 48 and the circular wall 12. The block 50 is further provided with an upper curved surface 52 having a radius of curvature identical to that of the adjacent surface of wall 12. The block is adapted to move laterally within groove 42 into and out of a wedged position much in the same manner as the rollers 40a and 40b illustrated in FIG. 1. A third embodiment of the invention is illustrated in FIG. 4 as comprising an elongated groove 54 again having a bottom 56 sloping downwardly in a direction opposite to that of the drive direction of the piston. In this embodiment the radius of the piston has been purposely cut down to accommodate a larger locking device 58, the latter being provided with a curved upper surface 60 designed to be seated tightly against the adjacent inner surface of curved wall 12 when the locking device 58 is moved into an operative wedged position by virtue of a force being exerted on the piston in a counterclockwise direction.

In view of the foregoing, it should now be apparent to one skilled in the art that the above-described embodiments each include the feature of a locking device contained within a groove having a bottom which slopes downwardly in a direction opposite to the drive direction of the engine. The locking devices cooperate with the grooves in which they are carried to prevent rotation of the pistons in one direction without in any way impeding rotation of the pistons in the other direction. The locking devices as well as the groove configurations may be varied considerably without departing from this basic concept.

The advantages of the present invention are primarily in the simplicity and reliability of the locking devices combined with the fact that when in a wedged position the devices each provide an improved seal between the pistons and the circular housing wall 12.

It is my intention to cover all changes and modifications of the embodiments herein chosen for purposes of disclosure which do not depart from the spirit and scope of the invention.

I claim:

1. For use with a rotary engine having a plurality of pistons mounted for rotation about a common axis within an annular chamber, said chamber having at least one circular wall surrounding said axis, means carried by each piston for preventing rotation thereof in one direction without impeding rotation of said piston in the opposite direction, said means comprising: a groove in the surface of said piston opening towards said circular wall, said groove extending in a direction parallel to said common axis across the full width of said piston, the bottom of said groove sloping downwardly in said one direction from a shallow end to an opposite end of increased depth, and locking means extending the entire length of said groove and movably positioned therein, said locking means being adapted for wedged engagement between the bottom of said groove and said circular wall when said piston exhibits a tendency to rotate in said one direction, the said wedged engagement being sufficient to prevent piston rotation in said one direction while at the same time providing an effective seal between the bottom of said groove and said circular wall.

2. The apparatus as set forth in claim 1 wherein said locking means is provided with a lateral dimension measured radially from said common axis which is at least equal to the minimum radial distance between the bottom of said groove and said circular wall, the maximum lateral dimension of said locking means, again measured radially from said common axis, being less than the maximum radial distance between the groove bottom and said circular wall.
